UNITED STATES PATENT OFFICE

2,577,438

STEP STOOL

Nathan Sussman, Long Island City, N. Y.

Application April 22, 1950, Serial No. 157,509

1 Claim. (Cl. 228—30)

1
The present invention relates to a step stool and in particular to means for retaining the ladder in the respective operative and inoperative positions.

Step stools or chairs are well known which are equipped with a step ladder, the latter being turnable from its inoperative position below the seat into operative position in front of the stool or chair. Different constructions provided different means for limiting turning movement of the step ladder into the respective operative and inoperative positions. While the inoperative position of the step ladder permitted of easy lifting of the chair or stool without further turning of the step ladder, the operative or outside position of the step ladder could not be retained upon lifting the stool or chair.

It is, therefore, one object of the present invention to provide a step stool or chair, the step ladder of which is retained in its inoperative and operative position regardless whether the stool or chair is positioned on the ground or lifted.

It is another object of the present invention to provide a step stool or chair having a step ladder turning upon an axle from inoperative to operative position, which axle include means for limiting the turning movement.

With these and other objects in view which will become apparent in the following detailed description, the present invention will be clearly understood in connection with the accompanying drawing, in which:

Figure 1 is a perspective view of the step stool; Fig. 2 is a sectional elevation along the lines 2—2 of Fig. 3;

Fig. 3 is a fragmentary view of the abutting means for the turning axle; and

Fig. 4 is a fragmentary view of the abutting means for the turning axle shown in a turned position.

Referring now to the drawing, the stepping stool or chair comprises four legs, preferably formed of two substantially vertically disposed U-shaped members preferably of tubular material with inverted U, thus providing two pairs of legs 1 and 2. The bases 3 and 4 of each pair of legs are secured to a third horizontally disposed U-shaped member 5, the base 6 of the member 5 connecting the two first mentioned U-shaped members at their front while the legs 7 of the member 5 extend parallel in rearward direction and are secured to the bases 3 and 4 of the two first mentioned U-members. The horizontally disposed legs 7 may be bent upwardly

to extensions 8 which are adapted to support a back 9 while the legs 7 are adapted to support a seat 10.

Front and rear braces 11 and 12 connect the front legs and rear legs 1 and 2, respectively. It is of course possible to provide also side braces (not shown) between each front and rear leg.

A step ladder 13 is turnably secured between the front legs 1, 2 of the chair or stool. The step ladder 13 comprises two approximately S-shaped preferably tubular members 14 which are welded or otherwise secured to another brace 15 rotatably mounted in the tubular front legs 1 and 2. In operative position of the step ladder 13 the members 14 comprise a short top horizontally disposed portion 16 which at its rear end is bent into a vertically disposed portion 17 to be bent forwardly into another horizontally disposed portion 18 of at least double length of the portion 16 to be bent downwardly at its front end to vertically disposed portions 19 of predetermined length which terminate at the ground on which the legs 1 and 2 rest. The horizontal portions 16 and 18 support steps 20 and 21, thus forming the ladder.

In the operative position of the ladder 13, as shown in Fig. 1, special abutting means are provided to retain the ladder 13 in this position even upon lifting the chair or stool from the ground.

In order to achieve this end, the brace 15 is eccentrically inserted into the front legs 1 and 2 of the stool in such manner, that the distance between the center of the brace 15 from the rear wall of the tubular legs 1 and 2 is shorter than that from the front wall thereof. Furthermore, the ends of the brace 15 have bores 22 which receive pins 23 extending in an angle in downward and rearward direction from the brace 15 when in the ladder 13 is in operative position. The tubular members 14 are preferably welded to the brace 15 in such manner, that when the ladder 13 engages the ground the pins 23 abut the inner face of the rear walls of the tubular legs 1 and 2 and prevent further turning of the ladder. The pins 23 thus reach the abutting position shown in Fig. 3 when the ladder 13 is in operative position.

The ladder 13 may be turned upon the brace 15 into rearward inoperative position in which case the pins 23 move counter clockwise (Fig. 3) and since the pins 23 due to their eccentric position within the tubular legs 1 and 2 pass the inner face of the front wall of the legs 1 and 2, the ladder 13 may be turned until the former vertical portions 19 thereof abut against the base

6 of the U-shaped member 5, the pins 23 thereby reaching approximately the horizontal position shown in Fig. 4. The ladder 13 is in the inoperative position completely under the chair or stool and in order to return the ladder 13 into operative position it is merely necessary to turn it upon the brace 15 clockwise until the pins 21 abut the rear inner face of the legs 1 and 2.

It is quite clear and evident that the brace 15 could be arranged also closer to the inner front face of the tubular legs 1 and 2 in which case the pins 23 must extend in an angle in forward and upward direction in order to abut the inner front face of the tubular legs 1 and 2.

I claim:

In a step stool or chair, a seat, a plurality of hollow legs supporting said seat, a step ladder turnably disposed between two of said legs, a brace rotatably mounted in said two hollow legs and secured to said step ladder, said brace being disposed eccentrically to the axis of said legs, a

5 pin member inserted at each end of said brace within said legs and abutting against the inner face of the wall of lesser distance of said legs when said step ladder is in operative position and said pin member of the brace passing freely the inner opposite face of said legs when said step ladder is turned upon said brace from operative into inoperative position within said chair.

10 NATHAN SUSSMAN.
